UNITED STATES PATENT OFFICE

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK

ACOUSTIC DEVICE

Application filed October 11, 1927, Serial No. 225,500, and in Germany October 21, 1923.

This invention relates to sound wave transmission systems, and particularly to sound translating devices, such as phonographs and electrical loud speakers, in which sound wave energy is transmitted as mechanical vibrations. The present application is continuing as to the subject matter of my co-pending application Serial No. 610,977, filed January 6, 1923, and as to certain parts of my co-pending applications Serial Nos. 628,168, filed March 28, 1923, and 33,619, filed May 29, 1925. The broad principles of the invention and their application, as hereinafter described, to sound converting systems in general are disclosed in the said co-pending application Serial No. 610,977; the particular embodiment of the invention in a stylus operated phonograph, also described herein, is disclosed in my co-pending application Serial No. 33,619; and the acoustic features of the sound amplifying horn, which forms part of the present invention, are disclosed in my co-pending application Serial No. 628,168.

An object of the invention is to improve the response-frequency characteristic of sound translating systems, whereby sound wave energy of all frequencies in the important range of speech and musical tones may be efficiently transmitted, and the sound waves faithfully recorded or reproduced. Another object is to improve the coupling between the mechanical portion of a sound translating system and the air, so that conversion of the wave energy is effected with uniform high efficiency at all frequencies. A co-related object is to effect in an improved manner the damping of resonance vibrations in the mechanical system of an acoustic translating device by the energy radiation properties of the sound radiating means.

In acoustic systems the translation of sound wave energy into other modes of vibration is most commonly effected by means of a vibrating diaphragm, or analogous device, which is set in motion by the impinging sound waves, or which is mechanically driven and imparts its energy to the air as sound waves. The diaphragm may be arranged to radiate or absorb sound wave energy directly, or it may be coupled to the free air by

means of a tapered horn. The mechanical system attached to the diaphragm may in turn be coupled to an electromagnetic driving or converting means, or it may be connected to a mechanical source of vibrations, for example, a stylus engaging the groove of a phonograph record. The system as a whole, whatever the particular arrangement may be, constitutes a wave transmission line along which the vibratory wave energy is transmitted in accordance with the general laws of wave propagation. Due to the masses and elasticities of the component parts, the mechanical portion of the system as a rule possesses one or more natural periods of vibration, in consequence of which the frequency-response characteristic for forced vibrations is markedly distorted by resonance at these frequencies.

In accordance with this invention the vibrating system of an acoustic translating device is treated as a wave transmission line of composite character, partly mechanical and partly acoustical. The distortion of the frequency-response characteristic due to resonance is recognized to be identical with distortion due to wave reflection, and is eliminated by so arranging and proportioning the elements of the system that waves of all frequencies in the desired range are transmitted through the system from end to end without suffering reflection. Each portion of the line is adapted to have the inherent capability of transmitting all of the desired frequencies without substantial loss. In addition, in order that the inherent transmission characteristics may be fully developed and utilized, the characteristic impedances of the several portions are matched to each other and to the impedance of the radiating device, which constitutes the terminal load for the system. The matching of the impedances may be achieved by making the different portions of the line similar with respect to their mechanical properties, or it may be effected by the introduction of suitable impedance transformation means.

An essential element of the system is a sound radiator capable of radiating wave energy with uniform high efficiency at all

5 frequencies in the speech or musical range. Such a radiator provides a terminal load for the mechanical line which has a substantially constant and resistive impedance, and if the impedances of the other portions of the line are properly matched thereto, the constant resistance becomes characteristic of the system as a whole.

10 It has already been noted that distortion due to wave reflection may be identified with distortion due to resonance in the vibrating system. Regarding the system as a resonant combination, the matching of the various line sections to each other has the effect of distributing the natural periods of vibration more or less uniformly through the transmission range, and of making them susceptible of uniform damping by means of a single resistive element at the end of the line. Matching 15 the resistance of the radiator to the impedances of the line sections provides just the correct amount of damping to make the response uniform at all frequencies in the transmission range.

20 25 The term impedance is here used in its general sense to define the ratio of an applied simple harmonic vibratory force to the resulting velocity of the system or body to which the force is applied. In this sense it is applicable to vibration systems of all types regardless of the nature of the medium or the character of the force. The characteristic impedance of a line is defined as the impedance of the line when it is assumed to be 30 infinitely extended. This quantity is descriptive of the properties of any short section of the line, although it does not by itself determine all of the properties. If the line is not uniform but is made up of coupled sections of "lumped" impedance elements, for 35 instance a chain of masses coupled by springs, each section of the line may have its own characteristic impedance, which is defined as the impedance of a line made up of an infinite number of recurrent sections of that particular type. Lines of the lumped impedance 40 type, as distinguished from uniform lines, are markedly selective in their wave transmission characteristics, but by arranging the coupling 45 of the elements in a particular manner and proportioning them in accordance with prescribed impedance values, such lines may be adapted to transmit freely waves of all frequencies within a predetermined wide range. 50 Structures of this type are known as broad band wave filters. For a more complete discussion of their properties reference is made to the Bell System Technical Journal, Vol. I, No. 2, Physical theory of the electric wave 55 filter, by G. A. Campbell.

60 In the preferred embodiment of the invention, hereinafter described in detail, the sound radiating means consists of a tapered horn in which the cross sectional area of the conduit 65 varies according to an exponential law with

distance along the axis. The horn is energized by, or imparts energy to, a diaphragm coupled to the small end by an air chamber in the usual manner. A feature of the invention relates to the proportions of the air chamber and the diaphragm whereby the elasticity of the included air is co-ordinated with the impedance coefficients of the other line elements, and whereby the impedance of the horn is matched to the impedance of the 70 mechanical system.

75 Other features relate to the construction of the horn, particularly with regard to the form and proportions of the sound conduit, whereby the range of uniform transmission 80 and radiation efficiency is extended downwards to include the lowest audible frequencies.

85 Additional features are concerned with particular constructions for the elimination of undesired elastic and frictional restraints in the mechanical system, whereby the response is maintained at a uniform level down to the lowest frequencies of speech, and with methods for increasing the rigidity and lightness 90 of the elements, so that the response characteristic is not impaired at high frequencies.

95 In its broader aspect the invention is not restricted to any particular type of radiator, but contemplates, rather, constructions whereby the flow of energy through the system and into the air is not impeded by the presence of conditions giving rise to wave reflection. Other types of sound radiator 100 may be used without departing from the spirit of the invention, the principal requirement being that the radiating efficiency should be high at all frequencies in the desired range.

105 In the detail description which follows the invention is described as applied to phonographs and electrical loud speakers. It will be evident, however, that the principles disclosed may be embodied in other structures, and in acoustic translating systems for other purposes, as indicated by the scope of the appended claims.

110 Referring to the drawings,

135 Fig. 5 shows in conventional form the impedance structure of the system of Fig. 4;

140 Fig. 6 shows diagrammatically typical response-frequency characteristics of a phonograph such as has been regarded as standard

in the prior art, and one embodying the invention;

5 Figs. 7 and 8 show in perspective and in cross sectional elevation a complete phonograph machine embodying the invention;

Figs. 9 and 10 illustrate the detail construction of one form of phonograph sound box in which various features of the invention are embodied; and

10 Figs. 11 to 14 illustrate other details of another sound box construction in which additional features of the invention are involved.

The diagrammatic representation of an electrical loud speaker in Fig. 1 illustrates 15 a more or less ideal arrangement of the vibratory system in accordance with the invention. The mechanical portion comprises a magnetic armature 1 pivoted at its center, a diaphragm 3 and an elastic coupling rod 2 connecting the 20 diaphragm to the armature. The armature is polarized by permanent magnet 7, and is caused to vibrate by oscillating currents flowing in coils 6, the driving force on the armature being proportional to the intensity of

25 the current. The acoustical part of the system comprises an air chamber 4, in front of the diaphragm and a tapered horn 5 the small end of which is connected to an aperture in the air chamber. The horn may be regarded

30 as an acoustic transmission line along which compressional waves are propagated in the well known manner. At the mouth of the horn the waves, which have approximately plane wave fronts, act upon the surrounding

35 air in much the same manner as would a large flat diaphragm or piston vibrating in the mouth of the horn. The air chamber 4 has a two-fold action. In the first place it acts as a velocity transformer by which a relatively small velocity at the surface of the dia- 40 phragm is made to produce a much larger air velocity in the throat of the horn. This is evident, since all of the air displaced by a

45 movement of the diaphragm naturally tries to escape through the smaller area of the horn opening. Due to its compressibility, however, the air displaced by the diaphragm does not all escape into the horn, but some part remains in the chamber and increases

50 the air pressure therein. The air chamber thus acts also as though it were an elastic spring, coupling the diaphragm to the air in the horn. The diaphragm is illustrated as a simple plunger or piston fitting closely into the air chamber. It is free from any elastic restraint other than what is applied by its coupling to the armature and by the elasticity of the air chamber. For the present purposes the diaphragm is assumed to be sufficiently 55 rigid so that it moves without bending, and so, may be regarded as a simple mass element.

Various ways by which these conditions may be closely approximated will be described later.

60 The mechanical parts together with the air

chamber constitute a linked chain of simple mass and elastic elements, or a line of the lumped impedance type. Coupled to this line by the air chamber, in its function as a transforming device, is the homogeneous 70 line formed by the horn, and the terminal load consisting of the free air at the horn mouth.

Before proceeding to discuss the proportioning of the system in accordance with the 75 principles of the invention, the nature of the impedances of the various elements will be considered and the impedance values defined. If a vibratory force is applied to a simple mass element, assumed free from external restraints, the motion of the body is resisted only by its inertia. The body undergoes a vibration synchronous with the force and of such amplitude that the alternating inertia reactions just balance the applied force. The impedance is directly proportional to the frequency, and since there is no energy dissipation it is purely reactive. The value of the impedance of a body of mass m in grams is equal to $j\omega m$ c. g. s. units 80 where $\omega = 2\pi$ times the frequency, and j is the usual complex operator indicating that the 85 value is imaginary.

When a vibratory force is applied to a 90 spring the force is balanced at all instants 95 by the elastic restoring force due to the displacement of the point of application. The amplitude corresponding to a constant force is the same at all frequencies, and hence the vibrational velocity increases in direct proportion to the frequency. Defining the elasticity as the ratio of the total force to the linear displacement at the point of application, and denoting this quantity by s the 100 impedance of an elastic element is equal to 105 $-j\frac{s}{\omega}$.

In the case of acoustic systems the wave motion takes place under the action of a vibratory pressure superimposed on the normal 110 pressure of the air. "Acoustic impedance" is defined as the ratio of the superimposed pressure intensity to the volumetric rate of displacement of the air past a given cross 115 sectional area of the system. For the present purposes, however, it is more convenient to use the impedance value defined as the ratio of the total pressure over the cross sectional area to the linear velocity of the air particles. This value corresponds directly to the definition of the impedance of the mechanical parts; it will therefore be termed the mechanical impedance to distinguish from the accepted definition of 120 acoustic impedance.

125 Fig. 2 is an impedance diagram corresponding to Fig. 1, in which the nature and the arrangement of the impedance elements are indicated by customary electrical symbols and conventions. The mass elements have 130

impedances analogous to that of an electrical inductance, and the elastic elements correspond to condensers. The masses m_1 and m_3 correspond to the armature and the diaphragm, respectively. These constitute "line," or "series," elements, so called because their motion is the proper motion of the system. The elasticities s_2 and s_4 corresponding to coupling rod 2 and air chamber 4, are shown as "shunt," or "coupling," elements. These serve to transmit the force from one line element to the next without diminution, but in so doing may abstract some of the velocity. The line elements, 15 while transmitting the vibrational velocity without diminution, tend by their reactions to absorb some of the impressed force. The transformer T_4 represents the transforming property of the air chamber. The horn is represented by the tapered line L_5 , conventionally indicated, and the load impedance R which corresponds to the impedance of the free air as seen from the horn mouth.

The proportioning of the various parts of the system in accordance with the invention requires that the numerical values of the impedances be known and also the variations of the impedances with frequency. Dealing first with the portion comprising the armature and diaphragm sections, this may be regarded as part of an extended mechanical line of the lumped impedance type, comprising a chain of mass elements, each of mass m , coupled in tandem by elastic elements, each of elasticity s . The line is a mechanical broad band wave filter and is adapted to transmit freely waves of all frequencies up to a limiting value f_c , defined by the equation

$$f_c = \frac{1}{\pi} \sqrt{\frac{s}{m}} \quad (1)$$

Throughout the greater part of this range the characteristic impedance approximates the constant value.

$$z_t = \sqrt{ms} \quad (2)$$

which is termed the nominal characteristic impedance. The exact value depends on the point at which the line is cut into to make the measurement, i. e. upon the impedance of the end element at point of measurement. Two particular terminations are of special importance. In the first the line terminates in a series element having half the impedance of the regular series element, and in the second the line ends in a shunt element having twice the impedance of a normal shunt element. These terminations, known respectively as "mid-series" and "mid-shunt", are unique in that the characteristic impedance is purely resistive at all frequencies in the transmission range. It is generally preferable to make use of one or

other of these terminations when the line is to be connected to a resistive load, or to another line having a resistive characteristic impedance. For this reason the elasticity s_4 of the air chamber is made equal to twice the normal elasticity of each coupling element of the assumed extended chain, for example, to twice the elasticity s_2 of the coupling rod. The mass m_1 of the armature is coupled to the electromagnetic driving system the impedance of which, as viewed from the mechanical side, is generally negligibly small. Impedance matching at this point is usually impracticable with the ordinary types of electromagnetic system, and, from the standpoint of uniformity of transmission efficiency, is of lesser importance, provided the impedances of the other portions of the system are matched. It has been found however that advantageous results are obtained by making the armature effective mass approximately equal to 0.8 of the mass of a normal line element. Since the armature motion is an angular vibration about its centre, it is the moment of inertia about this point, rather than the actual mass, that determines the impedance. The mass m_1 is the effective mass of the armature at the axis of linear motion passing through the centre of the diaphragm.

The foregoing considerations along with Equations 1 and 2 lead to the following explicit formulae for the impedance coefficients in terms of limiting frequency of the transmission range, and of the characteristic impedance:

$$\left. \begin{aligned} m_3 &= \frac{Z_t}{\pi f_c} = \frac{m_1}{0.8}, \\ s_2 &= \pi f_c Z_t = \frac{1}{2} s_4. \end{aligned} \right\} \quad (3)$$

The design of the horn as an efficient radiator will next be considered. As already stated, the requirement of uniform high radiation efficiency corresponds to the requirement of a constant resistive impedance at all frequencies in the desired range. In horn radiators two factors are involved in the determination of the radiation efficiency, first the characteristic properties of the horn, regarded as part of an infinitely extended wave transmission line, the impedance coefficients of which are tapered according to a prescribed law, and second, the radiating properties of the mouth. The characteristic impedance of any horn approaches a constant resistance as the frequency rises, but it is found that the constant value is attained most rapidly if the cross sectional area of the sound conduit varies according to an exponential law with the distance along the axis. In a horn of this type the cross sectional area, A_x , at a distance x from the

throat, is related to the throat area, A_o , by the formula

$$A_x = A_o e^{ax}. \quad (4)$$

The exponential factor a is termed the rate of taper and is equal to the fractional increase of area per unit length along the axis. A unique property of the exponential horn is that its transmission range is inherently limited at the low frequency end. An infinitely extended horn of this type would suppress all frequencies below a limiting value f_o given by the equation

$$f_o = \frac{ac}{4\pi} \quad (5)$$

in which c is the velocity of sound in air. Above this frequency all waves are freely transmitted.

Above the cut-off frequency defined by Equation 5 the characteristic impedance of the horn has a constant modulus value. At first it is largely reactive but rapidly becomes almost wholly resistive. At twice the cut-off frequency the resistance component has reached 86% of the final steady value and the reactive component is less than 60% of the resistance. The closeness with which the actual impedance of the horn approximates the characteristic impedance depends upon the amount of wave reflection at the mouth, or, in other words, upon the efficiency with which the horn mouth radiates energy to the free air. It has been found that the mouth of a horn is a poor radiator of vibrations having wave lengths greater than twice its diameter, the longer waves being largely reflected. The mouth of the horn should therefore be made of such diameter that it can radiate freely waves of the lowest frequency in the desired range. The conduit portion of the horn should be capable of freely transmitting all frequencies that the mouth can radiate. To this end the rate of taper should be such that the wave length corresponding to the cut-off frequency is greater than twice the mouth diameter. The optimum value is found to be numerically equal to π , but a range of values from three to four has been found satisfactory and in certain cases the rate of taper may be such that the wave length at the cut-off is as great as six times the mouth diameter without serious loss. When the cut-off wave length is greater than π times the mouth diameter the horn is capable of transmitting frequencies lower than the mouth can radiate and the mouth opening is therefore the factor that limits the response range. If the horn is straight and circular in cross-section the optimum relationship between the rate of taper and the mouth diameter may be expressed in other terms. For the optimum condition the radius of the mouth opening is equal to $\frac{2}{a}$,

where a is the exponential factor of Equation

4. Also, under this condition, the tangent to the outline of the horn at the mouth makes an angle of 45 degrees with the axis of the horn.

The optimum design is exemplified by a horn of exponential profile having a length of 38 inches, a mouth diameter of 22 inches and a throat diameter of 0.69 inch. For this horn the exponential factor a is 18.25 per cent per inch corresponding to a cut-off frequency of 196 c. p. s. or a wave length of 69 inches. The frequency at which the mouth opening begins to fail as a radiator is 300 c. p. s. corresponding to a wave length of 44 inches or twice the mouth diameter. Between 300 c. p. s. and 196 c. p. s. the radiation efficiency falls off gradually and at lower frequencies practically no sound is reproduced. The frequency equal to 1.5 times the cut-off frequency, which will be termed the pitch limit, may be taken as the limit at which horn assumes its maximum efficiency of response.

The steady value of the characteristic impedance varies from point to point of the horn in direct proportion to the cross sectional area. At the throat it has the value

$$Z_h = A_o c \rho \quad (6)$$

where ρ is the normal air density, and at the mouth its value is increased in proportion to the area. When the horn is proportioned in accordance with the foregoing rules the condition exists that the horn impedance is matched to the radiation resistance of the mouth opening, throughout the whole range of efficient radiation.

The function of the air chamber at the throat of the horn as a transformer is to match the horn impedance to the characteristic impedance of the mechanical system. The inclusion of the air chamber transformer in the system permits the mechanical elements to be designed more or less independently of the horn and to be given practicable proportions suited to the materials of construction. Where the diaphragm is of the simple plunger or piston type illustrated, the impedance transformation is readily computed. If the diaphragm area be denoted by A_1 , then the ratio of the air velocity v_1 at the diaphragm surface to the velocity v_o in the throat of the horn is given by

$$\frac{V_1}{V_o} = \frac{A_o}{A_1}. \quad (7)$$

Assuming for the moment that the air in the air chamber is incompressible, then, since there is no absorption of energy in the air chamber, the requirement that the energy imparted to the air by the diaphragm be equal to the energy delivered to the horn, gives rise to the relationship

$$v_1^2 Z_1 = v_o^2 Z_h,$$

in which Z_1 is the impedance of the acoustic

system as viewed from the diaphragm. The transformation ratio readily follows:

$$\frac{Z_1}{Z_h} = \left(\frac{A_1}{A_o}\right)^2. \quad (8)$$

- 5 The fact that the air in the air chamber is compressible is taken care of by including the elasticity of the air chamber as an impedance element in the mechanical system.
- 10 The air chamber elasticity is defined as the ratio of the increased pressure load on the diaphragm, due to the change of air volume, to the corresponding linear displacement of the center of the diaphragm. To compute its 15 value the air chamber is treated as a completely enclosed space, and the pressure and volume changes are assumed to follow the adiabatic law of expansion. On this basis the elasticity is found to be given by the 20 formula

$$s_4 = \frac{\rho c^2 A_1^2}{V} \quad (9)$$

in which V denotes the air chamber volume, 25 and in which the other factors have the values already defined.

The foregoing formulae enable the design of the system in accordance with the invention to be completely carried out. The upper 30 limiting frequency of the desired transmission range is an important factor in determining the proportions of the mechanical elements, and the lower limiting frequency controls the size and the rate of taper of the 35 horn. Any one of the elements of the mechanical system may be chosen as the starting point for the design, but as a rule the practical considerations surrounding the construction of the diaphragm make it most desirable 40 to choose that element as the starting point. The dimensions and mass of the diaphragm having been chosen, the values of air chamber and coupling rod elasticities are readily computed in terms of the diaphragm 45 mass and the upper limiting frequency, by means of Equation 3. The effective mass m_1 of the armature is directly related to the armature mass. The determination of the actual physical dimensions required to give 50 the desired mass and elasticity coefficients follows well known rules of mechanical design. The volume of the air chamber is determined from the diaphragm area and the desired elasticity by means of Equation 9.

55 The matching of the horn impedance to the characteristic impedance of the mechanical system remains to be accomplished. The latter impedance is fixed by the foregoing design procedure. The horn impedance is determined 60 by the throat diameter, and may be made any desired value, within limits, by properly choosing the length of the horn. The principle of impedance matching requires that the horn impedance multiplied by 65 the transformation ratio of the air chamber

transformer should equal the characteristic impedance of the mechanical system. This is expressed by the equation

$$Z_h x \left(\frac{A_1}{A_o}\right)^2 = Z_t, \quad 70$$

from which, by Equation 6,

$$A_o = \frac{A_1^2 c_p}{Z_t} \quad (10) \quad 75$$

The dimensions of the air chamber in accordance with the requirements of elasticity and impedance transformation may also be related to other impedance coefficients of the system, and the cut off frequency by additional formulae which are readily derived from the foregoing equations. Thus, the ratio of the air chamber opening areas, in terms of the cut off frequency and the diaphragm mass is given by the equations 85

$$\frac{A_1}{A_o} = \frac{\pi f_c m}{c_p A_1} = \sqrt{\frac{\pi f_c m}{c_p A_o}}. \quad (11)$$

The volume of the air chamber in terms of 90 the horn impedance and the cut off frequency is given by the equations

$$V = \frac{Z_h}{2\pi f_c c_p} = \frac{c A_o}{2\pi f_c}, \quad (12)$$

and in terms of the diaphragm mass and the factors entering into the horn impedance by

$$V = \frac{m}{2\rho} \left(\frac{A_o}{A_1}\right)^2. \quad (13)$$

The average depth of the diaphragm is given by the equation

$$\frac{V}{A_1} = \frac{\rho c^2}{2\pi^2 f_c^2} \times \frac{A_1}{m}, \quad (14)$$

and is inversely proportional to the mass per unit area of the diaphragm. These equations are useful guides in the design of a matched impedance system, and indicate the manner in which the air chamber dimensions should vary as the design requirements are changed. 110

In the foregoing formulae c. g. s. units are assumed; the factor c_p entering into the horn impedance has the approximate value 41 at ordinary pressures and temperatures; and the factor $c^2 p$ in Equation 9 has the value 1.4×10^6 . 115

To illustrate the effect of departure from the matched impedance condition, the response-frequency characteristics of a typical system of the type shown in Fig. 1 have been computed. These are shown in Fig. 3. The ordinates represent the variations of the energy level of the radiation, measured in standard transmission units, for a constant input force. Logarithmic scales are used for both co-ordinates to correspond with the laws of perception of tone pitch and loudness. Curve A corresponds to the condition in which the impedance matching is carried out in ac- 120 125 130

cordance with the foregoing formulæ; curve B shows the effect of making the horn impedance three times as great as the impedance of the mechanical system; and curve C the effect of reducing the horn impedance to one third of its proper value. The constant input force is adjusted to make the low frequency response the same in each case. Somewhat similar distortions result if the 10 horn mouth is made too small, or if the different sections of the mechanical system are not matched to each other.

In establishing the design rules it has been assumed that the diaphragm is of a simple 15 piston type in which all parts move equally with the centre. In actual practice the diaphragm will be clamped at its edge and will suffer bending of some form as it is vibrated. The bending of the diaphragm has a two-fold 20 effect. In the first place the particles of the diaphragm do not all move with the same velocity and do not contribute equally to the inertia reaction at the driving point, and in the second place the elemental surface areas 25 have different displacements and do not contribute equally to the compression of air in the air chamber. If the law of bending is known, or can be found experimentally, the effective mass of the diaphragm at the driving 30 point can be found by well known analytical methods. The effective area can be determined also by well known methods, this being defined as the area of a rigid piston which, for the same motion of the driving point, will 35 produce the same air displacement as the flexible diaphragm. Methods for determining the effective mass and effective area of an ordinary flat diaphragm clamped at its edge are described by Hanneman and Hecht, 40 (Sound Fields and Sound Antennæ, Engineering, London, February 14, 1919, page 224), and by Kennelly and Taylor, (Proceedings of the American Philosophical Society, Vol. 54, May 1915, pp. 96-136).

45 The clamping of the diaphragm also introduces an additional elastic restraint on the motion of the armature which is noticeable particularly at low frequencies. The effect of this restraint is principally to increase the 50 impedance of the system at low frequencies by adding an elastic reactive component that increases as the frequency diminishes. To maintain the response at a high level for the 55 lowest frequencies of speech or music it is desirable that the elastic restraints on the line elements, that is the "series" elasticities, should be as small as possible.

The carrying out of the invention in detail will be described in connection with a 60 mechanical phonograph, the vibrating system of which is illustrated diagrammatically in Figs. 4 and 5. The system includes the customary elements, namely, a stylus holder, a diaphragm, and a horn together with an air 65 chamber for coupling between the diaphragm

and the horn. In addition an elastic spider member is provided for coupling between the stylus arm and the diaphragm, the purpose of this element being to distribute the driving force more uniformly over the surface of the 70 diaphragm. The impedance elements of the system are shown in conventional form in Fig. 5, and the corresponding mechanical parts are identified by like symbols in Fig. 4.

The first part of the system comprises the 75 stylus and stylus arm. The latter is pivoted at an intermediate point and by virtue of its leverage it acts to transform the needle point velocity before impressing it on the diaphragm. In addition to the transforming 80 property, these elements possess mass and elasticity. The elasticity of the needle absorbs some of the velocity imparted to the needle point by the record, and acts therefore as a shunt impedance at the input end. 85 The mass of the needle arm furnishes an inertia reactance, and its elasticity constitutes a coupling impedance in shunt to the remainder of the line. In Fig. 5 the needle arm is represented by the transformer T_1 , mass m_1 , 90 and elasticity s_2 , the mass m_1 being taken as the effective mass of the needle arm at the diaphragm end. This section corresponds to the armature and coupling rod of Fig. 1, and the impedances are similarly designated. The 95 second part comprises the spider element consisting of a cupped disc with a number of elastic radial arms the ends of which are attached to the diaphragm. This element is represented by the line mass m_2 , corresponding 100 to the solid centre, and the coupling elasticity s_3 , corresponding to the arms. The third section comprises the diaphragm and air chamber combination, represented in Fig. 5 by mass m_3 and elasticity s_4 . The fourth part 105 consists of the acoustic load and includes the air chamber in its transformer aspect indicated by T_4 , and the radiator impedance Z_4 . These are the essential impedance elements of 110 the system. There are, however, additional 115 impedances present due to the elastic restraints introduced by the methods of supporting and connecting together the essential line elements. The elasticity s_7 represents the restraint on the needle arm movement due to 120 the pivot support, elasticity s_6 represents the restraint on the spider element due to bending at the point of connection to the needle arm, and s_5 represents the elastic restraint on 125 the diaphragm due to the clamping of its edge. By proper mechanical constructions, details of which will be described later the additional series elasticities may be made sufficiently small, so that their effect upon the response characteristic is unimportant. In a 130 system of the type illustrated the most important of the series elasticities is the elasticity of the diaphragm. From the stand-point of wave filter theory, the presence of the series elasticity establishes a lower cut-off 135

frequency at the natural period of the clamped diaphragm, and results in the attenuation of waves of lower frequencies. The upper limit of the transmission band is definitely related to the frequency at which the clamped diaphragm resonates with the elasticity of the air chamber, the horn opening being assumed closed, and is substantially equal to $\sqrt{2}$ times that frequency. Although the attenuation at frequencies below the lower band limit is small, it is desirable that this limit be placed as low as possible, by reducing to a minimum the series elasticity due to clamping. A convenient check on the design of this portion of the system is provided by determining the two resonance frequencies, and noting the interval between them.

The following design calculations illustrate the values of the impedance coefficients in one practical embodiment of the invention. To include substantially all of the frequencies of musical tones the limiting frequencies of the transmission range are set at 100 c. p. s. and 5000 c. p. s., the former determining the rate of taper of the horn, and the latter the cut-off frequency of the mechanical system. Taking the diaphragm as the starting point, the practical considerations relate to obtaining a light structure with sufficient rigidity to enable it to vibrate as a solid piston. A suitable design consists of a disc of duralumin .0051 cms. (.002") thick and 2.03 cm. (0.8") radius to the edge of clamping ring. To secure the desired rigidity the diaphragm may be concentrically corrugated over the greater part of its surface, the outer edge being left flat to provide a highly flexible support. The effective mass of this type of diaphragm is nearly equal to its actual mass, and the effective area to the actual area. Assuming a density of 2.8 for duralumin the diaphragm mass is found to be

$$m_3 = 0.186 \text{ gms.}$$

From Equations 1 and 2 the characteristic impedance of the mechanical system is

$$Z_1 = \pi f_c m_3 \\ = 2920 \text{ c. g. s. units.}$$

For uniformity of the different sections of the mechanical line the spider mass m_2 and the effective mass m_1 of the needle arm should equal the mass of the diaphragm. The normal value of the coupling elasticity corresponding to s_2 and s_3 is also found from Equations 1 and 2 to be

$$s_2 = s_3 = \pi f_c Z_1 \\ = 46 \times 10^6 \text{ c. g. s. units.}$$

The air chamber elasticity, in accordance with the rule for terminal impedances should have twice the normal elasticity, or

$$s_4 = 92 \times 10^6 \text{ c. g. s. units.}$$

The needle elasticity s_1 as seen from the diaphragm side of transformer T_1 may have the

twice normal value, but it is preferable to use a smaller elasticity than this, approximately equal to the normal value divided by 0.8. This is because the driving source, a record driven by a motor, being powerful enough to impart its velocity to the needle point regardless of the impedance of the system, most nearly corresponds to a source of infinite impedance and infinite force. There is therefore no consideration of impedance matching and the smaller effective stylus elasticity is found to give a somewhat improved response characteristic at the higher frequencies. The eight-tenths shunt termination is analogous to the eight-tenths series termination in the electrical system of Fig. 1.

The stylus elasticity is generally determined by the type of stylus available. An ordinary full tone needle may be chosen in which case the elasticity s_1 has the approximate value 80×10^6 ; this has to be adjusted to the desired effective value by giving the needle arm the proper transformation ratio. If the length of the needle arm from the pivot to the diaphragm driving point be denoted by l_1 and the length from the pivot to the needle point by l_2 , the velocity transformation ratio is equal to $l_1 \div l_2$ and the impedance ratio to $l_2 \div l_1$. The proper stylus arm ratio is thus found to be

$$\left(\frac{l_2}{l_1}\right) = \sqrt{\frac{46 \times 10^6}{80 \times 10^6}} = 0.85.$$

With the chosen diaphragm radius of 2.03 cms. the distance l_1 may conveniently be 2.54 cms. (1 inch) in which case the proper distance from the needle point to the pivot axis would be 2.15 cms. (.85 inch).

The volume of the air chamber to give the proper elasticity is found from Equation 9;

$$V = \frac{\rho c^2 A_1^2}{s_1} \\ = \frac{1.4 \times 10^6 \times 13^2}{92 \times 10^6} \\ = 2.58 \text{ cm.}^3 \quad 110$$

the effective area A_1 of the diaphragm being 13 square cms. If the diameter of the air chamber is the same as that of the diaphragm, the average depth will be 0.182 cms. (.047 inch).

The throat area of the horn required for the proper impedance matching is found by Equation 10 to be 2.4 square cms. corresponding to a diameter of 1.75 cms., or 0.7 inch.

The horn cut-off frequency was set at 100 c. p. s. This corresponds to a rate of taper of 3.65% per cm. of length, or 9.25% per inch of length. The diameter of the horn mouth, assumed circular, should be about one quarter of the wave length at the cut-off frequency; this works out to the 86 cms., or 34 inches. The mouth of the horn need not be

circular but if of other shape it should have the same area as the circular mouth of the computed diameter. The length of the horn corresponding to these dimensions is found to be 84 inches. By increasing the rate of taper very slightly so that the cut-off frequency is increased to 115 c. p. s. the horn length may be reduced to 72 inches.

In the foregoing example, the mechanical system has a relatively low characteristic impedance, this being due to the especially light diaphragm construction made possible by the use of a corrugated thin duralumin sheet. For a flat diaphragm of the ordinary type it is necessary to use thicker material to obtain a satisfactory degree of rigidity, and in consequence the mass of the diaphragm and the characteristic impedance of the mechanical system are correspondingly increased. To effect the proper matching between the horn and the higher impedance mechanical system resulting from the use of a heavier diaphragm, it is necessary to reduce the area of the horn throat in the same proportion as the mechanical system impedance is increased. At the same time it is necessary to reduce the volume of the coupling air chamber in a like proportion, to provide the proper value of elasticity to cooperate with increased diaphragm mass. For example, assuming a flat diaphragm of duralumin, (density 2.8) of area 17.8 square cms. and thickness .024 cm., (.0095 inch), the design formulae show that for a cut-off frequency of 6,000 c. p. s. the characteristic impedance of the mechanical system is 22,600 c. g. s. units. The horn throat area, as found by equation 10, is .575 cm.², corresponding to a diameter of .855 cm. or approximately .34 inch. The air chamber volume is found to be .528 cubic centimeters and the average depth to be .03 cms., or .012 inch.

In Fig. 6 curve A represents the response characteristic of a phonograph constructed substantially in accordance with the foregoing dimensions, and curve B that of a recognized phonograph of the prior art. It will be noted that below 1000 c. p. s., the response of the prior art phonograph falls off very rapidly and below 250 c. p. s. there is practically no response whatever. The characteristic of the phonograph constructed in accordance with the invention shows a uniform response that does not begin to fall off noticeably until the frequency is lower than 200 c. p. s. and is still high at frequencies as low as 125 c. p. s. Uniform transmission is maintained down to the limiting frequency defined by the horn mouth diameter, and a fair response is obtained at frequencies down to the horn cut-off. An increased range in the higher frequencies is also obtained and the response is much more uniform throughout the whole range.

A preferred manner of constructing the

horn so that, in spite of its considerable length, it may be included in a compact phonograph cabinet, is shown in Figs. 7 and 8. According to this arrangement the complete horn comprises a swinging tone arm 40 coupled to the sound box 42, and a box type folded horn 41. The exponential law of the cross sectional areas is carried through both portions. The folded part of the horn comprises a mouth or bell portion of rectangular cross section, divided into upper and lower sections 43 and 44 by a horizontal heart shape block 45. Two of the walls of the bell portion may be parallel in which case the desired rate of taper is obtained by adjusting the divergence of the other two walls and the cross sectional shape of the dividing block 45. The back of the bell is curved in conformity with the cross section of the block 45 so that the two sound conduits 43 and 44 are curved forward at the rear to connect with a second pair of horizontal tapered passages cut in the interior of the block. These passages are directed forward through the block, and, as they narrow down, they are turned backwards again to enter a curved vertical conduit 46, which rises up to the tone arm. The form of the sound passages is shown by the dotted lines in the perspective view of Fig. 7, and the general mode of construction of the central block is indicated by Fig. 8. The divergent passages carried in block 45 are symmetrical and of equal length so that in effect they constitute a single passage. In the bell portion the two passages 43 and 44 may be of unequal cross sectional areas if desired, but the axial length of the passage should be the same in each case. It has been found to be of some advantage with respect to the radiation of the higher frequencies to have one of the passages smaller than the other. There is also the incidental advantage that in case it is desired to place record racks in the mouth of the horn the larger records may be more readily stored in the larger opening. Since the passages converge again at the mouth and are of the same length the whole mouth area is effective for the radiation of low frequencies. A practical construction of the mechanical system is illustrated by the sound box shown in Figs. 9 and 10. This comprises a solid back plate 14, having a central opening and a projecting boss for attachment to the tone arm, and a perforated cover plate 11 to enclose the vibrating elements. The vibrating elements comprise a diaphragm 12 assembled between flexible gaskets 13 and clamped between the back plate and the cover by means of the screwed ring or nut 15. The diaphragm is preferably made of light thin material such as thin duralumin sheet and is stiffened by forming in any suitable manner. As shown, it is provided with a number of concentric corrugations of different depths, the outer part being left flat to keep the elastic restraint

due to clamping at a negligibly small value. The diaphragm is driven by a spider element 16, having a hemispherical portion 17, and a plurality of flexible arms radiating outwardly, and secured to the ridge of one of the corrugations in any suitable manner, such as by riveting, welding, or cementing.

The stylus arm 27 at its upper end bears on a projecting boss 28 at the centre of the spider 10 and is flexibly tied thereto by a U-shaped spring 26, one arm of which passes through a hole in the boss, while the other engages a notch in the back of the stylus arm. A socket 30 in the lower end of the arm carries the stylus 32, which is clamped in position by 15 thumb-screw 31. The stylus arm is carried by a bracket 20, attached by screws 19 to the casing 11, and is pivotally supported on downwardly projecting knife edges, 24 and 25, 20 which engage with grooves in a hardened rod 33 fitted to the arm. The knife edges are formed on a plate 21 attached to the bracket 20. A stiff spring rod 34 also fitted to the 25 stylus arm serves to hold the pivot members in contact. The ends of the spring rod engage in pivot screws 35 and 36 threaded into the turned out ends 37 and 38 of the bracket 20. The holes in these screws are conical, as also are the ends of the rod, and by adjusting 30 the screws some variation of the bearing pressure can be obtained. The pivot screws are so positioned that the spring support is in line with the knife edges, this being desirable for the purpose of keeping the elastic restraint on 35 the pivot as small as possible.

Figs. 11, 12, 13, and 14 show another form of vibratory system and stylus arm mounting especially well suited to the invention. For the sake of clearness, the case has been 40 omitted. The stylus bar 50 is pivotally supported in ball bearings in a U shaped bracket 51 of magnetic material, attached to the case in any suitable manner. Each arm of the bracket is provided with a tapered ball race 45 opening away from the stylus arm 50 which is supported on a permanently magnetized mounting 52. Each end of the mounting 52 is slightly tapered and the balls 53 forming the bearings are held snugly in place by the 50 magnetizing force of the mounting itself. This force automatically compensates for any wear on the pivots. End plate covers 54 may be used to prevent sudden jars from dis- 55 placing the balls and to prevent excessive side movement of the mounting.

The upper portion of the stylus arm 50 carried by the mounting 52 is made of thin sheet material having the form of a U shaped channel. The diaphragm is preferably made 60 of a duralumin about .0017" thick and is concentrically corrugated to render its central portion 56 substantially rigid. The clamping edge 55 is flat and the portion 57 between the clamping edge and the central portion is 65 provided with a series of tapered corruga-

tions which are substantially tangential to the outer corrugation of the central part. The form of the corrugations is indicated by Fig. 13 which shows the section along the chord 13, 13' in Fig. 11. It has been found 70 that this type of corrugation renders the diaphragm very flexible at this point, and reduces any tendency of the edge to resonate within the voice range. The upper end of the stylus bar 50, as shown in Fig. 14, is 75 flanged and provided with a resilient bifurcated projection 58 extending at right angles to the diaphragm. This bifurcation is notched on the outside near its end. The diaphragm carries a spider 59 similar to 16 80 of Fig. 9 with the exception that it has a large central aperture for receiving the bifurcated projection of the stylus arm. The edge of the aperture in the spider engages the notches in the projection of the stylus arm. This provides a self-supporting knife-edge pivot at 85 this point which has negligible series elasticity.

Although the two forms of vibratory systems described herein are especially well 90 adapted to the invention, it is obvious that other forms may be readily devised, the essential points being that the impedance be matched throughout the system and that the series elasticities be kept as low as consistent 95 with commercial structures.

A sound energy transmission system such as has been described in which the impedances are matched throughout, will transmit energy 100 in either direction without substantial reflection losses, and the phonograph herein described is suited for recording sounds as well as reproducing sounds. It is to be understood that where the term "phonograph" or the expression recorder and reproducer is 105 used in the claims, it is intended to define the system of the invention when used either as a sound recorder or reproducer.

The characteristic curves given in Figs. 3 and 6, it will be noted, are plotted in transmission units, (TU), the significance of 110 which is described in an article by W. H. Martin published in the Journal of the American Intitute of Electrical Engineers for June, 1924. The significance of the curves will be better understood when it is realized that the average ear fails to detect variations of less than 5 TU, so that variations in amplitude as great as 8 TU are consistent with high 115 quality of reproduction.

What is claimed is:

1. A sound translating system comprising sound radiating means and a mechanical vibratory system coupled thereto, the masses and elasticities of all of the elements which 125 influence the sound wave transmitting properties of said system being proportioned with respect to one another and to the impedance of the sound radiating means, and with relation to the range of frequencies to be trans- 130

- mitted, substantially as described, to give to the system as a whole a response characteristic which is sensibly constant throughout a frequency range of at least $2\frac{1}{2}$ octaves within the limits of essential speech frequencies.
5. A sound translating system according to claim 1 in which the various elements are proportioned substantially as described to give to the system as a whole a response characteristic which is sensibly constant throughout a frequency range of greater than $3\frac{1}{2}$ octaves within the limits of essential speech frequencies.
10. 2. A sound translating system according to claim 1 in which the various elements are proportioned substantially as described to give to the system as a whole a response characteristic which varies less than eight transmission units throughout a range of $2\frac{1}{2}$ octaves.
15. 3. A sound translating system according to claim 1 in which the various elements are proportioned substantially as described to give to the system as a whole a response characteristic which varies less than eight transmission units throughout a range of $2\frac{1}{2}$ octaves.
20. 4. A sound translating system according to claim 1 in which the various elements are proportioned substantially as described to give to the system as a whole a response characteristic which varies less than fifteen transmission units throughout the range of frequencies between 150 and 1000 cycles.
25. 5. A sound translating system according to claim 1 in which the various elements are proportioned substantially as described to give to the system as a whole a response characteristic which is sensibly constant throughout a frequency range representing more than one octave in the frequency range below 1000 cycles per second.
30. 6. An acoustic device in accordance with claim 1 in which the mechanical vibratory system comprises a plurality of substantially uniform sections, each having mass effectively in series and elasticity effectively in shunt, the masses and elasticities being proportioned to constitute the transmission line a broad band wave filter.
35. 7. An acoustic device comprising sound radiating means, and a mechanical vibratory system coupled thereto, the masses and elasticities of the elements of said system being so proportioned with respect to the range of frequencies to be transmitted, and to the impedance of the sound radiating means, that the combination of the vibratory system and the radiating means presents a mechanical impedance to vibrations impressed thereon, which is substantially uniform and resistive throughout a band of frequencies exceeding $2\frac{1}{2}$ octaves within the range of essential speech frequencies.
40. 8. An acoustic device in accordance with claim 1 in which the radiating means has a radiating area of such size that its radiation impedance is substantially constant and resistive at all audible frequencies above 200 cycles per second.
45. 9. A sound translating device comprising in combination a horn adapted by its rate of taper and its mouth opening to have a substantially uniform impedance throughout the essential range of speech and musical frequencies, and a mechanical vibratory system including a diaphragm coupled to said horn, the masses and elasticities of said vibratory system being proportioned and arranged to constitute a broad band wave filter having a transmission band exceeding $2\frac{1}{2}$ octaves in width within the range of essential speech frequencies, and having a nominal characteristic impedance, as measured at the junction point between the horn and the vibratory system, substantially equal to the horn impedance.
50. 10. In a sound translating device, a horn adapted by its rate of taper and its mouth opening to have a substantially uniform impedance throughout the essential range of speech and musical frequencies, a diaphragm operatively associated with the horn at its small end, and an air chamber disposed between the diaphragm and the horn, the mass of said diaphragm and the elasticity of the air chamber being proportioned to constitute a portion of a low pass wave filter having a cut-off frequency at least as high as 3000 cycles per second, and the area of the diaphragm being proportioned with respect to the area of the throat of the horn to effect the matching of the horn impedance to the nominal characteristic impedance of the wave filter.
55. 11. A sound translating device comprising sound radiating means and a mechanical vibratory system coupled thereto, said radiating means having a substantially uniform resistive impedance for sound waves of frequencies down to at least 200 cycles per second, and said vibratory system comprising masses and elasticities proportioned and arranged to constitute substantially a low-pass wave filter having a cut-off frequency at least as high as 3000 cycles per second, and having a nominal characteristic impedance substantially equal to the impedance of the sound radiator.
60. 12. An acoustic horn having an exponential variation of cross sectional area with the length, and having a rate of taper such that the horn transmits freely waves of all frequencies in the range of efficient radiation determined by the area of the mouth opening.
65. 13. An acoustic horn having an exponential variation of cross sectional area with the length, and having a mouth opening of diameter approximately equal to one quarter of the sound wave length corresponding to the cut-off frequency determined by the rate of taper of the horn.
70. 14. An acoustic horn having an exponential variation of cross sectional area with the length, and having a mouth opening of area approximately equal to the area of a circle the diameter of which is equal to one quarter of the sound wave length corresponding to the
75. 80. 85. 90. 95. 100. 105. 110. 115. 120. 125. 130.

cut-off frequency determined by the rate of taper of the horn.

15. A horn for sound transmission and radiation having a rate of taper at least as small as 20% increase of area per inch of length over a substantial portion of its length, and a mouth opening having an area equivalent to that of a circle of diameter substantially equal to one-fourth of the wave length correspondingly equal to the cut-off frequency determined by said rate of taper.

16. A horn for sound transmission and radiation corresponding to claim 15 in which the rate of taper is at least as small as 15% increase of area per inch of length over a substantial portion of its length.

17. A horn for sound transmission and radiation corresponding to claim 15 in which the rate of taper is at least as small as 10% increase of area per inch of length over a substantial portion of its length.

18. A sound translating system comprising an acoustic horn having a substantially constant impedance throughout the range of essential speech frequencies, a diaphragm and driving means therefor located at the small end of said horn, and an air chamber between said diaphragm and horn, said diaphragm, driving means, and air chamber, being proportioned with respect to their masses and elasticities to constitute a transmission line of substantially uniform characteristic impedance throughout the range of essential speech frequencies, and the area of the diaphragm being proportioned with respect to the area of the throat of the horn to effect the matching of the horn impedance to the characteristic impedance of said line.

19. In combination, an acoustic horn having a substantially constant impedance throughout the essential range of speech frequencies, a vibratory system including a diaphragm located at the small end of said horn, and an air chamber coupling said diaphragm to the horn, the area of the diaphragm being proportioned with respect to the area of the opening from said air chamber to the horn, to effect the matching of the horn impedance to the characteristic impedance of the vibratory system.

20. In combination, an acoustic horn, a vibratory system including a diaphragm located at the small end of said horn, and an air chamber coupling said diaphragm to the horn, said air chamber being proportioned with respect to its elasticity to co-operate with the masses and elasticities of said vibratory system in providing a mechanical wave transmission line of substantially uniform characteristic impedance throughout the essential range of speech frequencies.

21. In combination, an acoustic horn, a vibratory system including a diaphragm located at the small end of said horn, and an air chamber coupling said diaphragm to the

horn, the masses and elasticities of the elements of said vibratory system and said air chamber being proportioned and arranged to provide a multi-resonant system, having natural periods of vibration distributed in a regular manner throughout the range of essential speech frequencies, and said horn having a throat area at its point of connection to said air chamber such that the horn impedance provides substantially uniform damping of the vibrations of said system at all frequencies in the resonance range.

22. An acoustic device having a horn and a diaphragm coupled thereto by an air chamber, the ratio of the equivalent plunger area of said diaphragm to the area of the horn throat opening being numerically greater than the square root of the ratio of 10,000 times the effective mass of the diaphragm in grams, to 41 times the area of the horn throat opening in square centimeters.

23. An acoustic instrument having a diaphragm and a horn, the diaphragm having a mass, in grams, per square centimeter of its area at least as small as forty-three ten-thousandths of the ratio of the area of the small end of the horn to the equivalent plunger area of the diaphragm.

24. An acoustic device comprising a horn, a vibratory system including a diaphragm located at the small end of said horn, and an air chamber coupling said diaphragm and said horn, the ratio of the effective area of the diaphragm to the area of the throat of the horn being numerically greater than 250 times the quotient of the effective mass of the diaphragm in grams, divided by the effective area of the diaphragm in square centimeters.

25. An acoustic device comprising a horn, a vibratory system including a diaphragm located at the small end of said horn, and an air chamber coupling said diaphragm and said horn, the volume of said air chamber in cubic centimeters being numerically equal to the product of the effective mass of the diaphragm in grams, and the square of the ratio of the horn throat area to the effective area of the diaphragm, multiplied by a numerical factor lying between the values 340 and 420.

26. An acoustic device comprising a horn, a vibratory system including a diaphragm located at the small end of said horn, and an air chamber coupling said diaphragm and said horn, said air chamber having an area substantially equal to that of said diaphragm, and an average depth, in centimeters, which is numerically less than seven ten-thousandths divided by the mass in grams per square centimeter of area of the diaphragm.

27. A system in accordance with claim 19 in which the ratio of the equivalent plunger area of the diaphragm to the area of the horn throat opening is numerically greater than the square root of the ratio of 10,000 times

the effective mass of the diaphragm in grams, to 41 times the area of the horn throat opening in square centimeters.

28. A system in accordance with claim 19 in which the ratio of the effective area of the diaphragm, to the area of the horn throat opening, is numerically greater than 250 times the quotient of the effective mass of the diaphragm in grams, divided by the effective area of the diaphragm in square centimeters.

29. A system in accordance with claim 19 in which the volume of the air chamber in cubic centimeters is numerically equal to the product of the effective mass of the diaphragm in grams, and the square of the ratio of the horn throat area to the effective diaphragm area, multiplied by a numerical factor lying between the values 340 and 420.

30. A system in accordance with claim 19 in which the air chamber has an area substantially equal to that of said diaphragm, and has an average depth, in centimeters, numerically less than seven ten-thousandths divided by the mass in grams per square centimeter of area of the diaphragm.

31. A system in accordance with claim 19 in which the volume of the air chamber in cubic centimeters, is numerically less than 1.7 times the area of the horn throat opening in square centimeters.

32. In an acoustic instrument, the combination of a horn, a diaphragm, and an air chamber coupling said diaphragm and said horn, in which the connecting opening between said horn and said chamber is approximately .7 inch diameter and the diameter of the equivalent plunger area of the diaphragm is approximately 1.6 inches, and the air chamber volume between the diaphragm and horn opening is at least as small as one-fifth cubic inch.

33. An acoustic instrument having a sound radiator such as a horn, and a vibratory system including a diaphragm co-operating with said sound radiator, the elements of said vibratory system constituting a mechanical transmission line having series masses and having both shunt and series elasticities, the sum of all of the series elasticities being at least as small as six million dynes per centimeter.

34. An acoustic device comprising a horn, a diaphragm located at the small end of the horn, and an air chamber coupling said diaphragm and said horn, said diaphragm being supported at its edge and being resonant at a frequency lower than 600 c. p. s. due to its own mass and elasticity, and the elasticity of the said air chamber being such as to make the combination of the air chamber and diaphragm resonant at a frequency higher than 2000 cycles per second.

35. An acoustic device comprising a horn, a diaphragm located at the small end of said horn, and an air chamber coupling said dia-

phragm to the horn, said diaphragm being supported at its edge by the air chamber enclosure, and the resonance frequency of the diaphragm, due to its own mass and the elastic restraint of its support, being separated from the resonance frequency of the diaphragm in combination with the air chamber by an interval of at least 1400 cycles per second.

36. An acoustic device comprising a horn, a diaphragm located at the small end of said horn, and an air chamber coupling said diaphragm and said horn, the effective mass of said diaphragm being restrained in its motion by a series elasticity due to its support, and being coupled to the horn by the shunt elasticity of the air chamber, said series elasticity being such as to resonate with the effective mass of the diaphragm at a frequency lower than 600 cycles per second, and said shunt elasticity being such as to increase the resonance frequency of the diaphragm to a value greater than 2000 cycles per second.

37. An acoustic phonograph having a horn, the effective length of which is more than 40 inches, and having matched impedance from the stylus point to the mouth of said horn throughout the essential speech frequency range.

38. A phonograph comprising a sound box, and a horn having substantially matched impedance from the stylus point to free air throughout the essential speech frequency range.

39. In combination a phonograph reproducer and recorder having matched impedance from the point of the stylus to the diaphragm inclusive, throughout the essential speech frequency range, and a horn having an effective length of at least 40 inches, and a mouth opening to free air the diameter of which is approximately one-fourth the wavelength of the lowest frequency to be transmitted.

40. A sound recorder and reproducer having a vibratory member and a stylus arm coupled thereto, a pivot support for said stylus arm, and a needle attached to the lower portion of said arm, in which the ratio of the distance from said needle point to the axis of said support, to the distance from the axis to the point of attachment to the vibratory member is approximately equal to the square root of the ratio of the needle point elasticity to eight-tenths the elasticity of the needle arm tip.

41. A sound recorder and reproducer having a stylus arm in which the square root of the ratio of the stylus arm tip elasticity to the stylus arm mass is greater than 10,000, a diaphragm, and a coupling means between said stylus arm tip and said diaphragm, having a ratio of shunt elasticity to series mass of the same order as the first mentioned ratio.

42. In a sound reproducer and recorder.

- having a stylus arm, an air chamber and a diaphragm therein, means connecting said stylus arm and said diaphragm, said means having substantially the same characteristic impedance as the combination of said diaphragm and a chamber throughout the range of frequencies of importance in speech and music. 5
43. A sound recorder and reproducer having a diaphragm and a casing therefor, said casing and diaphragm forming a chamber having a zigzag cross section. 10
44. A sound recorder and reproducer according to claim 43, wherein the radial cross section of the chamber increases progressively 15 in thickness towards the center.
45. In a sound recorder and reproducer, a corrugated diaphragm, all flat spaces of which have their natural frequencies above the voice frequency range. 20
46. A sound recorder and reproducer comprising a stylus bar, a concentrically corrugated diaphragm, a spider connecting said bar and said diaphragm, said spider having a stiff central portion and flexible radial arms, 25 the stylus bar being connected to said central portion, and the ends of said arms being rigidly secured to a ridge of one of the corrugations of said diaphragm. 30
47. A sound recorder and reproducer according to claim 46, wherein the corrugations of said diaphragm are of unequal altitudes. 35
48. A sound recorder and reproducer according to claim 46, wherein the ratio of elasticity to mass of each corrugation is of such value as to give a critical frequency value above the range of importance in music and speech. 40
49. A sound recorder and reproducer having a corrugated diaphragm and a casing having a corrugated surface facing which matches the corrugations of said diaphragm. 45
50. A sound recorder and reproducer according to claim 49, wherein the corrugations in both diaphragm and casing are concentric. 50
51. A sound recorder and reproducer having a corrugated diaphragm and a casing forming a chamber, said casing having a corrugated surface facing, and being so disposed with respect to said diaphragm that the 55 velocity of the vibrations are substantially constant throughout the chamber. 60
52. A sound recorder and reproducer having a stylus arm and a diaphragm, means connecting said stylus arm and said diaphragm comprising a substantially rigid cup-shaped portion connected to said arm, and a plurality of elastic arms extending substantially radially from said cup portion connected to said 65 diaphragm. 70
53. A sound recorder and reproducer according to claim 52, wherein the stylus arm makes pivotal contact with the cup portion of said connecting means. 75
54. A sound recorder and reproducer hav- 80
- ing a diaphragm and a stylus arm, a spider connecting said stylus arm and said diaphragm, said spider having a substantially rigid perforated central portion, and elastic arms attached to said diaphragm, said stylus arm having a resilient end projecting through the perforation and resiliently engaging said spider. 79
55. A sound recorder and reproducer comprising a perforated vibratory member and a stylus arm, said stylus arm having a flanged end yieldingly engaging said vibratory member in the perforation thereof. 85
56. A sound recorder and reproducer comprising a vibratory member, and a channel-shaped stylus arm having a bifurcated flanged end yieldingly engaging said vibratory member. 90
57. A sound recorder and reproducer comprising a stylus bar, ball bearing pivots therefor, and magnetic means for maintaining the adjustment of the balls in said pivots. 95
58. In combination, a diaphragm, a diaphragm chamber enclosing the same, a horn, the cross-sectional area of which increases by 90 equal percentages for equal increases of distance from the small end, the diaphragm chamber opening into the small end of the horn, the rate of increase of said cross-section, and the cross sectional area of the small end 95 being such that the ratio of the damping of the diaphragm by said horn to the mass of the diaphragm is greater than 10,000 c. g. s. units. 100
59. In an acoustic instrument, a diaphragm chamber, a diaphragm therein, a horn, the cross section of which is an exponential function of the distance from the small end, the small end of said horn communicating with said diaphragm chamber, whereby the acoustic damping upon said diaphragm will be a function of the area of said small end of the horn, said area being so small that the acoustic damping per unit mass of the diaphragm is sufficient to prevent the ratio of sound energy radiated at the natural resonance period of the diaphragm to the sound energy radiated at the lowest frequency at which the horn can effectively radiate to be less than a normal ear can distinguish when listening to music. 105 110 115
60. In an acoustic instrument, a diaphragm chamber, a diaphragm therein, a horn, the cross section of which is an exponential function of the distance from the small end, the small end of said horn communicating with said diaphragm chamber, whereby the acoustic damping upon said diaphragm will be a function of the area of said small end of the horn, said area being so small that the acoustic damping is sufficient to prevent perceptible distortion over the range of frequency for which the horn is intended. 120 125
61. In an acoustic instrument, a diaphragm chamber, a diaphragm therein, a horn, the 130

- cross section of which is an exponential function of the distance from the small end, the small end of said horn communicating with said diaphragm chamber, whereby the acoustic damping upon said diaphragm will be a function of the area of said small end of the horn, said area being so small that the acoustic damping is sufficient to cause the radiated sound to be substantially independent of the frequency from the highest frequencies for which the instrument is intended to the cut-off frequency determined by the rate of increase of said horn. 5
62. In combination, a diaphragm, a horn, an enclosure housing said diaphragm and opening into said horn, said opening being as small, relative to the volume of said enclosure, as may be without causing the volumetric flow of air into said opening to be appreciably less than the volumetric rate of displacement of the diaphragm. 10
63. In combination, a diaphragm, means for vibrating said diaphragm, and acoustic means for so damping said vibration that the displacement of the diaphragm does not exceed an amount at which the restorative forces thereof cease to have a linear relation to said displacement. 15
64. In combination, a sound-reproducing device, a horn for acoustically damping the same, said horn having a cross-section which is an exponential function of the distance from the small end and having a bell with walls making a maximum angle of forty-five degrees with the axis, and a throat, the minimum diameter of which is so small that the acoustic damping is greater than the sum of all other damping. 20
65. In a sound-reproducing instrument, a horn, a diaphragm, an enclosure providing a chamber between said diaphragm and horn, said chamber opening into the throat of said horn, the area of said opening being large enough relative to the area of said diaphragm and volume of said chamber, to ensure the volumetric flow of air into the opening shall be equal to the volumetric rate of displacement of the diaphragm, and small enough to damp the motion of said diaphragm more than the sum of all other damping. 25
66. An acoustic horn, having an exponential variation of cross-section with the length and an internal diameter at the small end less than two per cent of the internal diameter at the large end. 30
67. An acoustic horn, having an exponential variation of cross-section with the length, the rate of increase of cross-section per unit length being sufficiently small to bring the pitch limit of accurate reproduction within an octave of middle C. 35
68. An acoustic horn, the area of whose cross-section is an exponential function of the distance from the small end, the rate of increase of the cross-section being less than twenty-five per cent per inch and the diameter of the opening at the small end being less than two per cent of the diameter of the opening at the large end. 40
69. In a sound-reproducing instrument, a diaphragm, a horn, a housing over said diaphragm opening into said horn, the height of said housing being less than fifty times the maximum amplitude of the motion of the diaphragm when loaded by said horn. 45
70. In a sound-reproducing instrument, a chamber having an opening, and means co-operating with said chamber to produce an air movement in said opening corresponding to the sound to be reproduced, the area of said opening being such that the pressure within the chamber is maintained substantially constant. 50
71. In combination, a diaphragm, a horn, an enclosure housing said diaphragm and opening into said horn, said opening being so proportioned, relative to the volume of said enclosure, that the volumetric flow of air through said opening will be substantially equal to the volumetric rate of displacement of the diaphragm. 55
72. In an acoustic instrument a diaphragm chamber, a diaphragm therein, a horn, the cross-section of which is an exponential function of the distance from the small end, the small end of said horn communicating with said diaphragm chamber, whereby the acoustic damping upon said diaphragm will be a function of the area of said small end of the horn, said area being so small that the acoustic damping per unit mass is greater than $\frac{\omega_r^2}{3\omega_1}$ where ω_r is the natural resonance frequency of the diaphragm and ω_1 is the lowest frequency which the instrument is expected to radiate. 60
73. In an acoustic instrument, a horn having a cross-section which is an exponential function of the distance from the small end, the rate of increase of said cross-section being less than twenty-five per cent per inch and the area of the large end being at least equal to that of a circle having $\frac{1}{a}$ for its radius, 65 where a is the constant in the exponent determining said rate of increase. 110
74. In an acoustic instrument, a horn having a cross-section which is an exponential function of the distance from the small end, the area of the large end being greater than the area of a circle having a diameter equal to one-sixth of the wave length of sound at the frequency of the lowest natural resonance pitch of the horn. 70
75. An acoustic horn having an exponential variation of cross-sectional area with the length and having a mouth opening of area equal to the area of a circle the diameter of 125

which lies between one-fifth and one-third of the sound wave length corresponding to the cut-off frequency determined by the rate of taper of the horn.

⁵ In witness whereof, I hereunto subscribe my name this 8th day of October, A. D. 1927.

HENRY C. HARRISON.
